Primary Examiner — Darlington Ly*Assistant Examiner* — Jeremy Koenig(74) *Attorney, Agent, or Firm* — Eric Hanscom(57) **CLAIM**

The ornamental design for a wheel, as shown and described.

DESCRIPTION

FIG. 1 is a perspective view of a wheel showing my new design; and,

FIG. 2 is a front elevation view thereof.

In the drawings, the broken lines depict portions of the wheel that form no part of the claimed design.
